INVENTOR.
C. L. LONG
BY
W. W. WALKER
ATTORNEY.

UNITED STATES PATENT OFFICE.

CLAUD L. LONG, OF DAYTON, OHIO, ASSIGNOR TO THE CRAWFORD, McGREGOR AND CANBY COMPANY, OF DAYTON, OHIO, A CORPORATION OF OHIO.

CUTTER-HEAD DRIVE FOR LAST LATHES.

Application filed November 27, 1920. Serial No. 426,755.

To all whom it may concern:

Be it known that I, CLAUD L. LONG, a citizen of the United States, residing at Dayton, in the county of Montgomery and State 5 of Ohio, have invented certain new and useful Improvements in Cutter-Head Drives for Last Lathes, of which the following is a specification.

This invention relates to pattern lathes 10 for turning articles of irregular shape such as shoe lasts, heads for golf clubs, and other variable shapes and forms, and more particularly to a motor drive mechanism and mounting therefor, for driving the cutter 15 heads, which may be mounted upon and travel with the cutter head carriage.

The object of the invention is to simplify the structure as well as the means and mode 20 of operation of such lathes, whereby they will not only be cheapened in construction, but will be more efficient in operation, positive in action, uniform in result, and unlikely to get out of repair.

A further object of the invention is to 25 eliminate the usual driving drum and the vibration, incident to its use.

A further object of the invention is to provide driving means for the cutter heads 30 independent of the motive power of the cutter head carriage, whereby the speed of the carriage and the cutter head, may be varied independent of each other.

A further object of the invention is to 35 provide positively connected driving means which will eliminate the use of drive belts, and to provide such driving means rigidly upon the cutter head carriage, in intimate relation with the cutter head shaft, whereby a balanced structure will be afforded.

With the above primary and other incidental objects in view as will more fully appear in the specification, the invention 40 consists of the features of construction, the parts and combinations thereof, and the mode of operation or their equivalents as hereinafter described and set forth in the claims.

Referring to the drawings, Fig. 1 is a top 45 plan view of the head of a pattern lathe, with the reciprocating carriage mounted thereon, illustrating the application of the improved motor drive mechanism forming the subject matter hereof to the present type

of lathe. Fig. 2 is a side elevation taken diagonally in relation with the bed of the 55 lathe, but parallel to the cutter head shaft. Fig. 3 is a detail view illustrating the relation of the driving gear and the motor, taken on line 3—3 of Fig. 2. Figs. 4 and 5 are detail plan view and side elevation 60 respectively of a modification of the construction illustrated in the preceding figures, wherein one of the cutter heads is mounted directly upon the armature shaft of the driving 65 motor, and the other cutter head shaft operatively connected therewith by intermediate gears.

Like parts are indicated by similar characters of reference throughout the several views.

Inasmuch as the present invention pertains only to the driving means for the cutter head shafts, and not to the lathe per se, only such portions of the lathe as are necessary to an understanding of the mechanism and operation have been illustrated in the 75 drawings. The lathe to which the invention has been shown applied is of the general type illustrated in patent to Eastman, 1,104,040, and more particularly that illustrated in pending application Serial No. 80 196,617 of Long and Schmaus.

As illustrated in these prior constructions the cutter head shafts of such lathes have usually been actuated by a drive belt from a large drum located in the lower portion 85 of the lathe structure. Some attempt has heretofore been made to eliminate the use of the large drum. Such constructions have usually retained the belt and the driving medium. A notable instance of such development is shown in patent to Morton 1,199,407, wherein a motor is suspended beneath the reciprocating carriage from which power is transmitted to the cutter head shaft 90 by a driving belt.

Belts have been found undesirable due to frequent slippage, and loss of power, and the short life of the belt incident to the high rate of speed, at which the cutter head shafts are driven. It is customary to drive the 100 roughing cutter of the construction shown in the drawings and hereafter described, at an approximate speed of 6000 R. P. M. while the finishing cutter is rotated at the rate of 7500 R. P. M. At such high speeds the slippage or loss of power is frequently equiva- 105

lent to from 300 to 500 R. P. M. and friction developed burns a leather belt, so that its average life is approximately ten days, while the fabric belts will last but a few months.

The present construction overcomes these difficulties by mounting a driving motor on top of the reciprocating carriage, and in juxtaposition to the driving shaft of the cutter head, with which it is interconnected for positive driving action by gears.

Referring to the drawings, 1 is the bed of the lathe having thereon the ways on which reciprocate the model carriage 3, and cutter head carriage 4. The mechanism for advancing these carriages in unison is shown and described in the prior patents and pending application heretofore mentioned, to which reference is to be had for detailed description.

Mounted in suitable bearings 5 in the traveling cutter head carriage is a drive shaft 6, carrying at its extremity a cutter head 7, which may be of any suitable type or construction. The cutter head shaft 6 is inclined to the path of travel of the carriage, whereby the cutter head 7 rotates in an oblique plane and is advanced laterally against the work. Mounted in similar bearings 9 and extending parallel with the roughing cutter shaft 6 is a shaft 10, also inclined to the path of travel of the carriage, carrying at its forward end a finishing cutter 11. The particular construction of the cutter heads 7 and 11, is described and claimed in the aforementioned pending application of Long and Schmaus. These cutter heads are disclosed in the present instance for illustrative purposes only and it is obvious that any other type of cutter head adapted to the work to be performed may be substituted therefor. The bearings 5 and 9 for the respective shafts in the present instance have been shown mounted upon a somewhat Z-shaped bracket 12, stationarily supported upon the traveling carriage 4. Mounted upon the lower and rearwardly extending shelf or ledge of this bracket 12 is an electric motor 14, upon the armature shaft 15 of which is carried a driving gear 16. The driving gear 16 meshes simultaneously with gears 17 and 18 upon the roughing cutter shaft 6 and finishing cutter shaft 10 respectively. The driven gears 17 and 18 are of different diameter whereby the respective shafts are driven at different rates of speed. To insure a uniform driving connection these gears are preferably though not necessarily spiral or helical gears. The driving motor being mounted directly upon the carriage in lieu of being suspended beneath affords a well balanced construction, and enables the power to be transmitted directly upon the motor shaft to the cutter head shafts of the intermeshing gears 16, 17

and 18, thereby eliminating driving belts and affording a positive driving connection. By this construction, the respective cutter head shafts, must necessarily be driven uniformly at their relative rates of speed, and no variation of speed of one or the other shafts can occur as is the case with belt driven devices. Furthermore, by the present construction, the driving of the cutter head shaft is accomplished entirely independent of the travel of the carriage, thereby enabling the speed of the carriage and that of the cutter head shaft to be independently regulated, according to the character of the work, or the material operated upon. While the present driving mechanism is applicable to cutter heads of various sizes, it is especially desirable for driving cutter heads of small size wherein high speeds are necessarily employed.

While in Figs. 1, 2 and 3 the intermediate gear 16 has been shown as the driving gear mounted upon the drive shaft of the motor, there has been shown in Figs. 4 and 5 a modification of this construction, wherein the motor shaft is extended as the cutter head shaft 6. That is to say, the cutter head shaft 6, bearing the roughing cutter also comprises the armature shaft of the motor 14, and the roughing cutter 7 is mounted directly upon this armature shaft. The shaft carries the same gear 17, which in this instance becomes the driving gear meshing with an idle gear 16', mounted upon a suitable bracket 20, attached to the supporting bracket 12. This intermediate idle gear 16' meshes with the gear 18 upon the finishing cutter shaft, whereby the respective shafts are driven in the same direction, at predetermined relative rates of speed. It is obvious that the motor shaft may be either the roughing cutter shaft or the finishing cutter shaft, in either instance the other shaft being driven thru the medium of the idler gear 16'.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific details shown, but that the means and construction herein disclosed comprise but one of several modes of putting the invention into effect, and the invention is therefore claimed in any of its forms or modifications within the legitimate and valid scope of the appended claims.

Having thus described my invention, I claim:

1. The combination with a pattern lathe including a reciprocatory carriage and a pair of rotary cutter heads mounted thereon, and operable simultaneously on a single piece of work, of a motor carried by the carriage and direct positive driving connections between the cutter heads and motor for driving said cutter heads simultaneously at predetermined relative rates of speed.
2. The combination with a pattern lathe including a reciprocatory carriage, a pair of parallel shafts mounted upon the carriage, a cutter head upon each shaft simultaneously engaging a single piece of work, a toothed gear on each shaft, an intermediate gear simultaneously meshing with both of the shaft gears, and a driving motor directly connected with one of said gears whereby the relative rate of rotation of the cutters is uniformly maintained.
3. The combination with a pattern lathe including a reciprocatory carriage and a pair of cutter heads comprising roughing and finishing cutters simultaneously operable on a single piece of work and cutter head shafts therefor mounted upon said carriage, of a driving motor carried by said carriage and so connected to drive both cutters that any variation in drive is common to both.
4. The combination with a pattern lathe including a reciprocatory carriage and a pair of parallel shafts disposed thereon in positions inclined to the path of travel of the carriage, and cutter heads carried by the said shafts and simultaneously engaging a single piece of work, of a driving motor and means operatively connecting the driving motor simultaneously with both cutter head shafts whereby said cutter heads will be rotated at different rates of speed in unvarying proportion, one to the other.
5. The combination with a pattern lathe including a reciprocatory carriage and a pair of parallel shafts disposed thereon in positions inclined to the path of travel of the carriage, and cutter heads carried by the said shafts comprising roughing and finishing cutters rotating at different rates of speed, a train of toothed gears, operatively connecting the shafts one with the other for simultaneous rotation, a driving motor carried by the carriage and operatively connected with said gear train whereby the relative rotation will be uniform.

In testimony whereof, I have hereunto set my hand this 9th day of November A. D. 1920.

CLAUD L. LONG.
